UNITED STATES PATENT OFFICE.

FREDERICK C. LAVARACK, OF ORANGE, NEW JERSEY.

MEANS FOR BONDING RAILS.

1,267,673.

Specification of Letters Patent.

Patented May 28, 1918.

Application filed January 8, 1914. Serial No. 810,974.

To all whom it may concern:

Be it known that I, FREDERICK C. LAVARACK, a subject of Great Britain, residing at Orange, in the county of Essex and State of New Jersey, have invented an Improvement 5 in Means for Bonding Rails, of which the following is a specification.

This invention relates to improved means for double bonding rails for railway signal work. Heretofore, so far as I am aware, when two bonds are employed for bonding rails for railway signal work, separate bonding means such as bonding-pins are provided for each bond, the bonding-pins being arranged side by side in a horizontal plane, and each bond-wire extends from the outermost pin at one end to the innermost pin at the other end, so that the bond-wires are quite long although of the same length. 15 Furthermore, the usual bonding-pin has a groove at one side for the wire and when the pin is driven into the hole in the rail, with the wire arranged in said groove, the support for the pin is unequal, and, as a result, it frequently tips and bends when struck with a sledge, and is ruined, particularly when great care is not exercised by the workman in driving it. 20

In accordance with this invention I employ two or more bond wires of the same length, all of which can be made shorter than the bond-wires usually employed, and secure all of the wires at one end to one of the rails by a single bonding-pin and all of the wires at the other end to the other rail by a single bonding-pin; and said bonding-pins have side grooves preferably equidistantly disposed to receive the ends of the bond-wires so that an equal support is provided for the pins in the holes, thereby enabling them to be driven into the holes with less liability of tipping or bending, even by a careless workman. As but a single bonding-pin is employed for each end of the plurality of bond-wires the expense of securing the bond-wires to the rails is considerably less than the present method of double bonding rails, the reduction being both in material and labor. 45

I am aware that broadly speaking a single attaching means for each end of a plurality of bond-wires has been suggested, but my invention is contrasted therewith in that my single attaching means consists of a single 50 element, which itself is adapted to be driven

into the hole in the rail and is held therein by friction only.

Figure 1 represents in side elevation the adjacent end-portions of two rails with bonding-means embodying this invention. 60

Fig. 2 is a side elevation, and

Fig. 3 a longitudinal transverse section of one of the bonding-pins.

Figs. 4 and 5 are views illustrating the method of securing the ends of the bond-wires to the rails by my improved bonding means. 65

10, 10 represent the adjacent portions of two rails which are or may be of any usual or suitable construction. A single cylindrical hole 12 is drilled through the web 15 of each rail to receive a bonding-pin and one of the ends of all of the bond-wires. 18 and 20 represent two bond-wires although a greater number may be employed if desired, which are of the same length, and which can be made shorter than the bond-wires usually employed. 75

25 represents one of the tapering bonding-plugs or pins having, as here shown, two 80 grooves 26, 28, at its sides, which are extended throughout its length, and of suitable size to receive the ends of the bond-wires. These grooves are preferably equidistantly disposed with respect to each other, so that 85 an equal support is provided for the pin when placed in the hole in the rail, and while being driven in, thus preventing it from easily tipping or bending when struck by the sledge. As an illustration of the manner of 90 attaching the ends of both bond-wires to a rail, one end of each bond-wire is projected through the hole in the rail and said ends are arranged in the side grooves in the pin and the pin is then thrust or started into the 95 hole by hand, as represented in Fig. 4, and then the exposed or outer end of the pin is struck one or more heavy blows with a sledge, driving it into the hole, as represented in Fig. 5, thereby firmly securing it and 100 the wires in place by friction.

The reason that the bond-wires herein employed can be made shorter than the bond-wires usually employed is that the single bonding-pins are disposed in substantially 10: the same places in the rails as are the innermost bonding-pins of the usual arrangement of double bonding-pins.

In addition to the reduction in cost incident to the employment of single bonding- 110

pins and shorter bond-wires than those usually employed, there is a substantial reduction in the cost of drilling, as herein but two holes are drilled in the rails instead of 5 four, thus saving time and labor; and on account of the bonding-pins being slightly larger in diameter than those usually employed, larger drills are employed for drilling the holes in the rails and the liability of 10 breakage is correspondingly reduced, thus resulting in a considerable saving.

The bonding-pins here shown are substantially the same as form the subject-matter of my application #796,715, filed October 22, 1913, to which reference may be had. 15

I claim:

A bonding pin for use in connecting the

terminals of a plurality of bonding wires to rails, comprising a tapered body formed with diametrically-opposed wire receiving grooves of uniform depth throughout and parallel with the tapered surface of the pin, to provide a wedge-shaped section between the bottoms of the groove, the grooves extending from end to end of the body and open at both ends.

In testimony whereof, I have signed my name to this specification, in the presence of two subscribing witnesses.

FREDERICK C. LAVARACK.
